UNITED STATES PATENT OFFICE

GABRIEL E. OSTROOT, OF MINNEAPOLIS, AND SAM WESTERHEIM, OF ST. PAUL,
MINNESOTA

WINDOW CONSTRUCTION

Application filed April 7, 1931. Serial No. 528,414.

This invention relates to window construction of that type including vertically sliding sashes, and the invention has for its object to provide, in a manner as hereinafter set forth, means for connection to the sashes and window frame for eliminating all friction when the sashes are shifted from and to normal position.

The invention further aims to provide, in a manner as hereinafter set forth, means for use in connection with windows for eliminating the commonly used parting stops which always are a source of trouble, either by collecting of paint or varnish or by the warping of the sash.

A further object of the invention is to provide, in a manner as hereinafter set forth, a means other than sash cords, sash weights and pulleys for holding the sash or sashes of a window in position when adjusted from normal and with such means so constructed and arranged to provide a thoroughly efficient weather stripping medium to exclude air, dust and moisture.

A further object of the invention is to provide, in a manner as hereinafter set forth, a thoroughly efficient weather stripping medium for use in connection with windows, and so constructed and arranged as to eliminate the binding of the sashes of the window relative thereto.

Further objects of the invention are to provide, in a manner as hereinafter set forth, in window construction means for the purposes referred to and which is simple in its construction and arrangement, strong, durable, compact, thoroughly efficient in its use, conveniently released to permit for readily shifting the sashes to and from normal position, quickly installed with respect to a window frame and window sashes, automatically locking the sashes in normal and suspended positions, and comparatively inexpensive to manufacture.

With the foregoing and other objects in view, the invention consists of the novel construction, combination and arrangement of parts as hereinafter more specifically described, and illustrated in the accompanying drawings, wherein is shown an embodiment

of the invention, but it is to be understood that changes, variations and modifications can be resorted to which fall within the scope of the claims hereunto appended.

In the drawings wherein like reference characters denote corresponding parts throughout the several views:

Figure 1 is a sectional elevation of an upper and lower sash of a window showing the adaptation therewith of the means for eliminating friction, parting stops and for suspending the sashes of the window frames when shifted from normal.

Figure 2 is a section on line 2—2 Figure 1.

Figure 3 is a section on line 3—3 Figure 1.

Figure 4 is a sectional detail of the lower sash.

Figure 5 is a perspective view of the attachment for the lower sash.

Figure 6 is a perspective view of one of the stationary latching elements.

Figure 7 is a perspective view of the resilient retaining element for the shiftable locking element.

Figure 8 is a perspective view of the shiftable locking element.

Figure 9 is a section on line 9—9 Figure 5.

Figure 10 is a perspective view of the actuating element employed on the upper sash.

Referring to the drawings in detail, 1 denotes a window frame and 2 an upper and 3 a lower sash slidably mounted in frame 1.

Each side rail 4 of sash 2 is formed with a transverse socket 5 opening at the outer side edge of the rail. The rail 4 is also formed with a slot 6 disposed at right angles to and communicating at its inner end with the socket 5. The slot 6 opens at the front face of rail 4.

Each side rail 8 of sash 3 is formed with a transverse socket 9 opening at the outer side edge of rail 8. The rail 8 is also formed with a slot 10 disposed at right angles to and communicating at its inner end with the socket 9. The slot 10 opens at the front face of rail 8.

Each side rail 4 of sash 2 has its outer edge formed from end to end thereof with a groove 12 of the same width as and which intersects the outer end of a socket 5. Each side rail 8

of sash 3 has its outer side edge formed from end to end thereof with a groove 13 of the same width as and which intersects a socket 9.

Secured to each side of the window frame 5 is a pair of combined sash guide and weather strip forming elements and as the elements of each pair are of like construction, but one will be described, as the description of one will apply to the other. One of the elements 10 of each pair of elements extends into the grooves of the upper sash and the other element of each pair of elements extends into the grooves of the lower sash. The elements of each pair of elements are indicated at 14, 15. The element 14 of one pair opposes the element 14 of the other pair. The element 15 of one pair opposes the element 15 of the other pair. The elements 14 extend into the grooves of the upper sash and the elements 15 20 extend into the grooves of the lower sash. The elements of each pair are spaced from each other.

Each element of each pair comprises a body portion in the form of a strip 16 of the desired width and thickness and of a length to extend from the top to the bottom of the window opening. The strip 16 is of bow shape cross section and has the inner corners of its lengthwise edges abut against the sides 30 of the window frame, as at 17. One side of strip 16 terminates in an outwardly directed, right angularly disposed resilient U-shaped extension 18 which provides a guide. One of the sides of extension 18 is of 35 greater length than the other side, as indicated at 19. The extension 18 is positioned in a groove in the outer side edge of the sash side rail. The strip 16 is formed with countersunk openings 19' for the passage of hold- 40 fast devices 20' for the purpose of anchoring the strip in position with respect to the window frame.

The extensions 18 of the elements 14, 15 are positioned on the outer sides of the strip 16 45 of such elements. The extensions 18 correspond in length to that of the strip 16.

Each sash is provided in each of its sockets with a resilient V-shaped retaining element 21 standing on its lower lengthwise edge. 50 The element 21 is formed from a resilient metallic strap bent upon itself to provide a curved bend 22 and a pair of oppositely inclined arms 23, 24 the former being of greater length than the latter. Each arm has its 55 vertical free edge formed with a rectangular notch 25. The bend 22 is cut away at its top and bottom to make it of less height than the arms 23, 24 and to provide upper and lower seats 26, 27 respectively and upper and lower 60 vertical shoulders 28, 29 respectively. The element 21 when in position has its arms extend towards the base and sides of the sockets. The element 21 is of less length than the depth of the socket.

65 Associated with each element 21 is a pair

of sash latching elements. The element 21 is arranged between said latching elements and the latter are indicated at 30, 31. The element 30 is stationary and the element 31 is 70 shiftable to latching position relative to element 30 by element 21. The elements 30, 31 acting on the sides of extension 18 and in connection with element 21 latch the sash in the position set. The elements 30, 31 oppose opposite sides of the socket, stand on their lower lengthwise edges and are arranged in 75 opposed spaced relation.

The element 30 comprises a rectangular body portion 32 which is lengthwise slotted and the part thereof freed by the slits is bent at right angles thereto to provide a combined supporting and coupling arm 33 having an inwardly extending right angularly disposed angle shaped free end 34. The arm 33 is arranged adjacent the inner end of body portion 32 and the latter has its other end formed with a right angularly disposed apertured flange 35 which is positioned and secured against the inner portion of the outer side edge of a sash side rail. The flange 35 opposes a strip 16 of an element 14 or 15. Holdfast means 36 are employed to secure flange 35 to the sash. Projecting inwardly from the body portion 33 adjacent the flanged end of the latter, disposed at right angles thereto and flush with the top and bottom edges thereof is a pair of superposed, right angularly disposed, spaced flat combined supporting and stop arms 37, 38 and each of which has its front side edge, in proximity to its free end formed with a notch 39.

The element 31 is in the form of a substantially rectangular plate 40 standing on its lower longitudinal edge and having a rounded outer end. The top and bottom edges of plate 40 are formed with rectangular notches 41, 42 respectively. The plate 40 is proximity to its rounded end is provided with a square opening 43.

When the locking elements 30, 31 are positioned relatively to each other and to a retaining element 21, the arms 37, 38 of element 30 are mounted respectively against the seats 26, 27 of element 21. The rear edges of the arms 37, 38 abut shoulders 28, 29 respectively of retaining element 21. The arms 37, 38 of element 30 are seated in and project from the notches 41, 42 respectively formed in element 31. The arm 33 of element 30 extends through the notches 25 formed in the free end of the arms of the element 21 and said arm 33 also extends through and projects from the opening 43 in element 31. The arms 23, 24 of retaining element 21 bear respectively against the opposed faces of elements 30, 31. The element 21 normally acts on element 31 to have its outer end exert pressure on side 19 of extension 18 to bend the other side of the latter against element 30 to latch the sash. The sash is released when the inner 130

or rear end of element 31 is shifted towards element 30 against the action of element 21.

Associated with each element 31 is a releasing member 44 therefor and which when active provides for the shifting of the inner end of element 31 towards the inner end of element 30 against the action of the arm 24 of the element 21. The member 44 includes a shank 45 of rectangular contour and which terminates at its inner end into a rectangular head 46 provided with an opening 47, through which extends the angle shaped end 34 of arm 33 for coupling member 44 against the outer side at the outer end of element 31. The arm 33 extends into an opening 6 or 10. The member 44 extends through an opening 6 or 10 and projects beyond the sash in which such member is arranged.

Associated with each of the members 44 arranged in the upper sash is an actuating element 48 therefor and associated with each of the members 44 arranged in the lower sash is an actuating element 49 therefor. Each of the actuating elements are vertically shiftable and arranged on the inner sides of the sashes. The element 48 is positioned in convenient reach.

Each actuating element includes a rectangular plate 50 provided with a centrally disposed oval shaped slot 51 at its longitudinal median and at a point between its transverse center and upper end, a pair of spaced aligning oval shaped slots 52, 53 in proximity to its lower end and between the longitudinal median of the plate and the side edges of the latter, and a rectangular slot 54 positioned in proximity to its upper end at a point between the longitudinal median of the plate and inner side edge thereof. A shifting member 44 extends through slot 54 and has a loose fit therein. The plate 50 is slidably connected to the sash by headed holdfast devices 53' extending through slots 51, 52 and 53. On the vertical shift of plate 50 it carries member 44 therewith and pulls the latter to act on element 31 to shift its rear end towards element 30.

Associated with each extension 18 and overlapped by the latter is a weather strip forming element 55 consisting of a plate 56 which is secured to the outer side portion of the other side edge of a sash and side rail, one side of plate 56 has projected therefrom at right angles thereto and into an extension 18 a U-shaped portion 57. At the other end of plate 57 is an angle shaped flange 58 which engages in the sash.

The actuating element 48 has extending therefrom a handle or finger and thumb grip 59 for vertically shifting the plate 50 of element 48.

The actuating element 49 has its plate 50 provided with an outwardly directed right angularly disposed notched arm 60 to which is loosely coupled a handle bar. Secured to

the lower sash is a bracket 62 which is notched and loosely coupled to handle bar.

The extensions 18 and portions 57 in connection with the strips 17 coact to provide a weather strip medium. The elements 55 are constructed of metal and are secured to a sash and by this arrangement if the sashes shrink they will have no effect upon the interfitting tight engagement between the extensions 18 and portions 57. The strips 17 are so secured in position that the inner corners thereof will bite into the window frame.

What we claim is: —

1. In window construction, a combined sash guide and weather strip forming element adapted to be secured to the side of a window frame and formed with an angularly disposed extension, a pair of opposed, spaced latching elements adapted to be mounted in the side rail of a window sash, one of said elements of said pair being shiftable and the other supporting the shiftable element, a resilient retaining element interposed between said latching elements and supported by the said other latching element and acting on said shiftable element of said pair, said extension positioned between the outer ends of said pair of latching elements and normally acted upon by said shiftable element for latching the sash in set position, a weather strip forming element adapted to be secured to the window sash and including a portion projecting into said extension, and means slidably carried by the window sash and coupled with the said other latching element for shifting the shiftable element against the action of said retaining element to release the sash.

2. In window construction, a combined sash guide and weather strip forming element adapted to be secured to the side of a window frame and formed with an angular extension, a pair of opposed, spaced latching elements adapted to be mounted in a window sash, one of said elements of said pair being shiftable and the other supporting the shiftable element, a retaining element interposed between said latching elements and supported by the said other latching element and acting on said shiftable element, said extension positioned between the outer end of said pair of latching elements and acted upon by said shiftable element for normally maintaining the sash in set position, a weather strip forming element adapted to be fixed to the sash and including a portion projecting into said extension, a shifting member for said shiftable element, and a movable actuating element adapted to be connected to the sash and engaging when moved with said member for actuating the latter to shift said shiftable element against the action of the retaining element to release the sash.

3. In window construction, a sash having its side rails provided with sockets and open-

ings extending at right angles to and communicating at their inner ends with said sockets, a pair of spaced opposed combined sash guide and weather strip forming elements adapted to be secured to opposite sides of a window frame and provided with extensions projecting into the side rails of the sash and across the mouth of the sockets, a pair of weather strip forming elements secured to the sides of the sash and including angularly disposed portions projecting into said extensions, a pressure exerting mechanism arranged in said socket and normally acting upon said extensions for latching the sash in set position, and shiftable means carried by the sash, extending through said openings and operatively associated with said mechanism for actuating the latter to relieve pressure on said extensions to release the sash.

20 4. In window construction, a sash having its side rails provided with sockets and openings extending at right angles to and communicating at their inner ends with said sockets, a pair of spaced opposed combined sash guide and weather strip forming elements adapted to be secured to opposite sides of a window frame and provided with extensions projecting into the side rails of the sash and across the mouth of the sockets, a pair of combined guide and weather strip forming elements secured to the sashes and including angularly disposed portions projecting into said extensions, a pressure exerting mechanism arranged in each socket and normally acting upon said extensions for latching the sash in set position, shiftable means carried by the sash, extending through said openings and operatively associated with said mechanism for actuating the latter to relieve pressure on said extensions to release the sash, said mechanism including retaining elements and shiftable latching elements acted upon by said retaining elements for exerting pressure on said extensions for latching the sash, and said means bearing against said shiftable elements.

5. In window construction, a sash having its side rails provided with sockets and openings extending at right angles to and communicating at their inner ends with said sockets, a pair of spaced opposed combined sash guide and weather strip forming elements adapted to be secured to opposite sides of a window frame and provided with extensions projecting into the side rails of the sash and across the mouth of the sockets, a pair of weather strip forming elements secured to the sash and including angularly disposed portions projecting into said extensions, a pressure exerting mechanism arranged in each socket and normally acting upon said extensions for latching the sash in set position, means carried by the sash, extending through said openings and operatively associated with said mechanism for

actuating the latter to relieve pressure on said extensions to release the sash, said mechanism including controlling elements and shiftable latching elements acted upon by said retaining elements for exerting pressure on said extensions for latching the sash, and said means bearing against said shiftable elements and including movable elements to provide for the operation of said means to actuate said mechanism to pressure relieving position to release the sash. 75

6. In window construction, a combined sash guide and weather strip forming element adapted to be secured to the side of a window and including an extension for projecting into the outer side rail of a sash, a weather strip forming element adapted to be secured to the sash and including an angularly disposed portion projecting into said extension, a pressure exerting mechanism adapted to be carried by the sash and normally acting on said extension for latching the sash in set position, and operable means adapted to be carried by the sash, coupled to said mechanism and when operated actuating said mechanism to relieve pressure on said extension to release the sash. 80

7. In window construction, a combined sash guide and weather strip forming element adapted to be secured to the side of a window and including an extension for projecting into the outer side rail of a sash, a weather strip forming element adapted to be secured to the sash and including an angularly disposed portion projecting into said extension, a pressure exerting mechanism adapted to be carried by the sash and normally acting on said extension for latching the sash in set position, operable means adapted to be carried by the sash, coupled to said mechanism and when operated actuating said mechanism to relieve pressure on said extension to release the sash, said mechanism including a retaining element, a shiftable latching element and a stationary latching element, said shiftable element acted upon by said retaining element exerting pressure on said extension for latching the sash, and said means connected to said stationary element and bearing against said shiftable element. 95

8. In window construction, a combined sash guide and weather strip forming element adapted to be secured to the side of a window and including an extension for projecting into the outer side rail of a sash, a weather strip forming element adapted to be secured to the sash and including an angularly disposed portion projecting into said extension, a pressure exerting mechanism adapted to be carried by the sash and normally acting on said extension for latching the sash in set position, operable means adapted to be carried by the sash, coupled to said mechanism and when operated actuat-

ing said mechanism to relieve pressure on said extension to release the sash, said mechanism including a retaining element, a stationary latching element and a shiftable latching element, the latter being acted upon by said retaining element for exerting pressure on said extension for latching the sash, and said means connected to said stationary element, bearing against said shiftable element and including a movable element to provide for the operation of said means to actuate said mechanism to pressure relieving position with respect to the extension.

9. In window construction, a combined sash 15 guide and weather strip forming element adapted to be secured to the side of a window and including an extension for projecting into the outer side rail of a sash, a weather strip forming element adapted to be secured to the 20 sash and including an angularly disposed portion projecting into said extension, a pressure exerting mechanism adapted to be carried by the sash and normally acting on said extension for latching the sash in set position, operable 25 means adapted to be carried by the sash, coupled to said mechanism and when operated actuating said mechanism to relieve pressure on said extension to release the sash, said mechanism including a stationary latching 30 element, a retaining and a shiftable latching element acted upon by said retaining element for normally exerting pressure on said extension, said stationary element including arms for coupling said means to said mechanism and for supporting said shiftable and 35 retaining elements, and said means bearing against said shiftable element.

10. In window construction, a combined sash guide and weather strip forming element 40 adapted to be secured to the side of a window and including an extension for projecting into the outer side rail of a sash, a weather strip forming element adapted to be secured to the sash and including an angularly disposed portion projecting into said extension, a pressure exerting mechanism adapted to be carried by the sash and normally acting on said extension for latching the sash in set position, operable 45 means adapted to be carried by the sash, coupled to said mechanism and when operated actuating said mechanism to relieve pressure on said extension to release the sash, said mechanism including a stationary latching element, a retaining and a shiftable latching 50 element acted upon by said retaining element for normally exerting pressure on said extension, said stationary element including arms for coupling said means to said mechanism and for supporting said shiftable and 55 retaining elements, and said means bearing against said shiftable element and including a movable element to provide for the operation of said means to actuate said mechanism to pressure relieving position with respect 60 to the extension.

11. In window construction, a sash having its side rails provided with sockets and openings extending at right angles to and communicating at their inner ends with said sockets, a pair of spaced opposed combined sash 70 guide and weather strip forming elements adapted to be secured to opposite sides of a window frame and provided with extensions projecting into the side rails of the sash and across the mouth of the sockets, a pressure exerting mechanism arranged in said socket and normally acting upon said extensions for latching the sash in set position, and shiftable means carried by the sash, extending through 75 said openings and operatively associated with said mechanism for actuating the latter to relieve pressure on said extensions to release the sash.

12. In window construction, a sash having its side rails provided with sockets and openings extending at right angles to and communicating at their inner ends with said sockets, a pair of spaced opposed combined sash 80 guide and weather strip forming elements adapted to be secured to opposite sides of a window frame and provided with extensions projecting into the side rails of the sash and across the mouth of the sockets, a pressure exerting mechanism arranged in each socket and normally acting upon said extensions for 85 latching the sash in set position, shiftable means carried by the sash, extending through said openings and operatively associated with said mechanism for actuating the latter to relieve pressure on said extensions to release the sash, said mechanisms including retaining elements and shiftable latching elements acted 90 upon by said retaining elements for exerting pressure on said extensions for latching the sash, and said means bearing against said shiftable elements.

13. In window construction, a combined sash guide and weather strip forming element adapted to be secured to a side of a window and including an extension for projecting into the outer side rail of a sash from the outer side edge of such rail, a pressure exerting mechanism adapted to be carried by such side rail of the sash and normally acting on said extension at a point within such side rail for latching the sash in set position, and operable means adapted to be carried by the sash and operatively associated with said mechanism and when operated actuating said mechanism to relieve pressure on said extension to release the sash.

14. In window construction, a combined sash guide and weather strip forming element adapted to be secured to a side of a window and including an extension for projecting into the outer side rail of a sash, a pressure exerting mechanism adapted to be carried by the sash and normally acting on said extension for latching the sash in set position, operable means adapted to be carried by the 125

sash, coupled to said mechanism and when operated actuating said mechanism to relieve pressure on said extension to release the sash, said mechanism including a retaining element, a shiftable latching element and a stationary latching element, said shiftable element acted upon by said retaining element exerting pressure on said extension for latching the sash, and said means connected to said stationary element and bearing against said shiftable element.

15. In window construction, a combined sash guide and weather strip forming element adapted to be secured to a side of a window and including an extension for projecting into the outer side rail of a sash, a pressure exerting mechanism adapted to be carried by the sash and normally acting on said extension for latching the sash in set position, 20 operable means adapted to be carried by the sash, coupled to said mechanism and when operated actuating said mechanism to relieve pressure on said extension to release the sash, said mechanism including a retaining element, a stationary latching element and a shiftable latching element, the latter being acted upon by said retaining element for exerting pressure on said extension for latching the sash, and said means connected to said 25 stationary element, bearing against said shiftable element and including a vertically movable element to provide for the operation of said means to actuate said mechanism to pressure relieving position with respect to 30 the extension.

16. In window construction, a combined weather stripping and latching means, said means including a stationary element adapted to be secured lengthwise of one side of a 40 window frame and formed with a right angularly disposed extension adapted to extend in the side rail of a window sash, a latching device adapted to be carried within such side rail and coacting with said extension for normally latching the sash in set position, and an element adapted to be secured to the outer side edge of such sash and formed with an angularly disposed portion seated in said extension.

50 17. In window construction, a combined weather stripping and latching means, said means including a stationary element adapted to be secured lengthwise of one side of a window frame and formed with a right angularly disposed extension adapted to extend in the side rail of a window sash, a latching device adapted to be carried within such side rail and coacting with said extension for normally latching the sash in set position, and 55 an element adapted to be secured to the outer side edge of such sash and formed with an angularly disposed portion seated in said extension, the said extension and angularly disposed portion being resilient and of U-shaped 60 contour in sectional plan.

18. In window construction, a pair of elements adapted to be secured to a side of a window frame and a side rail of a window sash and having coacting interengaging parts to provide weather stripping means, that element secured to the window frame being stationary and said part thereof extending into that side rail to which the other element is secured, the said parts being disposed at right angles to said elements, that element secured to the sash being bodily carried therewith and spaced from the said side of the window frame, and that part of the element carried by the sash nested within and having slidable engagement with said other part.

19. In window construction, a pair of elements adapted to be secured to a side of a window frame and a side rail of a window sash and having coacting interengaging parts to provide weather stripping means, that element secured to the window frame being stationary and said part thereof extending into that side rail to which the other element is secured, the said parts being disposed at right angles to said elements, that element secured to the sash being bodily carried therewith and spaced from the said side of the window frame, that part of the element carried by the sash nested within and having slidable engagement with said other part, and latching means adapted to be mounted within said rail and engaging with that part carried by the element secured to the window frame for latching the sash in set position.

20. In window construction, a pair of elements adapted to be secured to a side of a window frame and a side rail of a window sash and having coacting interengaging parts to provide weather stripping means, that element secured to the window frame being stationary and said part thereof extending into that side rail to which the other element is secured, the said parts being disposed at right angles to said elements, that element secured to the sash being bodily carried therewith and spaced from the said side of the window frame, that part of the element carried by the sash nested within and having slidable engagement with said other part, latching means adapted to be mounted within said rail and engaging with that part carried by the element secured to the window frame for latching the sash in set position, and slidable means operatively associated with said latching means and adapted to be connected to the window sash for releasing said latching means.

21. In window construction, a sash guide element for extension in the side rail of a window sash, a pair of opposed spaced latching elements adapted to be mounted in said rail, one of said elements of the pair being shiftable and the other supporting the shiftable element, a resilient retaining element interposed between said latching elements and

supported by said stationary element and acting on said shiftable element of the pair, said guide element extended between the outer ends of the latching elements and normally acted upon by the said shiftable element for latching the sash in set position, and means carried by the window sash and operatively associated with said other latching element for shifting the shiftable element 10 against the action of the retaining element to release the sash.

22. In window construction, a sash guide element for extension in the side rail of a window sash, a pair of opposed spaced latching elements adapted to be mounted in said rail, one of said elements of the pair being shiftable and the other supporting the shiftable element, a resilient retaining element interposed between said latching elements 20 and supported by said stationary element and acting on said shiftable element of the pair, said guide element extended between the outer ends of the latching elements and normally acted upon by the said shiftable element for latching the sash in set position, means carried by the window sash and coupled with said other latching element for shifting the shiftable element against the action of the retaining element to release the sash, said guide element providing a weather strip for a portion of the outer side edge of said rail, and an element secured to the rail and extending into said guide element to provide a weather strip for the remaining portion of the outer side edge of said rail.

23. In window construction, a sash guide element for extension in the side rail of a window sash, a pair of opposed spaced latching elements adapted to be mounted in said rail, one of said elements of the pair being shiftable and the other supporting the shiftable element, a resilient retaining element interposed between said latching elements and supported by the said other latching element 40 and acting on said shiftable element of the pair, said guide element extended between the outer ends of the latching elements and normally acted upon by said shiftable element for latching the sash in set position, a shifting member for said shiftable element, and a movable actuating element adapted to be connected to the window sash and engaging when upwardly moved said member for actuating the latter to shift said shiftable element against the action of the retaining element to release the sash.

24. In window construction, a sash guide element for extension in the side rail of a window sash, a pair of opposed spaced latching elements adapted to be mounted in said rail, one of said elements of the pair being shiftable and the other supporting the shiftable element, a resilient retaining element interposed between said latching elements and supported by the said other latching element

and acting on said shiftable element of the pair, said guide element extended between the outer ends of the latching elements and normally acted upon by said shiftable element for latching the sash in set position, 70 a shifting member for said shiftable element, a movable actuating element adapted to be connected to the window sash and engaging when upwardly moved said member for actuating the latter to shift said shiftable element against the action of the retaining element to release the sash, said guide element providing a weather strip for a portion of the outer side edge of said rail, and an element secured to the rail and extending into said guide element to provide a weather strip for the remaining portion of the outer side edge of said rail.

25. In a combined weather stripping and latching means for each side rail of a window sash, the combination with a window frame and a window sash having its side rails opposing and spaced from the sides of the window frame, each of said rails being formed with a lengthwise groove in its outer side edge, of a pair of vertical elements, each formed of a portion for securing against a side of the frame and a portion extending at right angles to the other portion and into a groove, a latching means carried within each side rail of the sash and normally engaging an angularly disposed portion for latching the sash in set position, a pair of vertical members, each secured to the outer side edge of a side rail of the sash and formed with a right angularly disposed portion nesting in and slidably engaging with an angularly disposed portion of a vertical member, and spaced means carried by the sash for actuating said latching means from latching engagement with the angularly disposed portions of said elements.

26. In combination, a window sash having a side rail formed centrally of its outer edge with a lengthwise groove terminating at the top and bottom of the rail, a strip adapted to be secured to a side of a window frame, opposing that portion of said outer edge adjacent one side of the groove and formed with a right angularly disposed extension positioned in and spaced from the side walls of the groove, latching means within said side rails and normally engaging the sides of the extension for latching the sash in set position, a strip secured against that portion of said outer side edge adjacent the other side of the groove and formed with an angularly disposed portion seated in said extension, and means carried by the sash for releasing the latching means from said extension.

27. In window construction, in combination, a pair of opposed latching elements for opposing and normally engaging a window sash guide extended into a side rail of a sash to lock the latter in set position, said elements

adapted to be positioned in such rail, one of said elements of the pair being shiftable and the other supporting the shiftable element, a retaining element interposed between said 5 latching elements and acting on said shiftable element, and an actuating element adapted to be carried by the sash and coupled with the shiftable element for shifting the latter against the action of the retaining element to 10 release the sash.

28. In window construction, two pair of latching elements, each pair adapted to be carried by a side rail of a window sash to normally engage a guide for the latter to 15 latch the sash in set position, one of the elements of each pair being shiftable and the other stationary, means positioned between the elements of each pair for normally maintaining them in engagement with a guide, 20 a shiftable member for and coupled with each shiftable latching element for shifting it against the action of the said maintaining means associated therewith to release the sash from the guide, and actuating means for said 25 shiftable members adapted to be carried by the sash.

29. In window construction, two pair of latching elements, each pair adapted to be carried by a side rail of a window sash to 30 normally engage a guide for the latter to latch the sash in set position, one of the elements of each pair being shiftable and the other stationary, means positioned between the elements of each pair for normally maintaining them in engagement with a guide, 35 a shiftable member for and coupled with each shiftable latching element for shifting it against the action of the said maintaining means associated therewith to release the sash 40 from the guide, and actuating means for said shiftable members adapted to be carried by the sash, the said actuating means being vertically movable and slidably connected to the sash.

45. 30. In window construction, a combined sash guide and weather strip forming element adapted to be secured to a side of a window and including an extension for projecting into the outer side rail of a sash from 50 the outer side edge of such rail, a pressure exerting mechanism adapted to be carried within said rail and normally acting on said extension at a point within said rail for latching the sash in set position, and vertically 55 movable, operable means adapted to be shiftably supported from one face of the sash, coupled to said mechanism and when operated in one direction actuating said mechanism to relieve pressure on the extension to release 60 the sash.

31. In window construction, a frame, a sash vertically slidable therein, sash guides supported on the frame, and means carried by the sash for gripping the guides, said means having 65 movable projecting parts adapted to be

moved and lifted for releasing said means and for lifting the sash.

In testimony whereof, we affix our signatures hereto.

GABRIEL E. OSTROOT.
SAM WESTERHEIM.
